UNITED STATES PATENT OFFICE.

THOMAS TURNER, OF OTTUMWA, IOWA.

ROCK-DRILL-FEEDING MECHANISM.

No. 843,718.

Specification of Letters Patent.

Patented Feb. 12, 1907.

Application filed May 9, 1906. Serial No. 315,978.

To all whom it may concern:

Be it known that I, THOMAS TURNER, a citizen of the United States; residing at Ottumwa, in the county of Wapello and State of Iowa, have invented a new and useful Rock-Drill-Feeding Mechanism, of which the following is a specification.

This invention relates to fluid-actuated mechanism for feeding motors, and more particularly pneumatic-hammer-operated drills, to their work, said invention being not limited to drills, but capable of successful employment in other relations.

In rock-drilling difficulty is experienced in varying the pressure of the feed mechanism on the motor in order to secure the proper holding power in stone or material of different characters. Thus, for instance, when a hole is being drilled in hard rock more pressure is required than in rock of softer character and a pressure adequate for the former will cause the drill to stick in the latter, so that trouble is experienced in turning the same.

One of the principal objects of the present invention is to provide novel and simple mechanism whereby the pressure upon the motor may be varied to a comparatively great extent in order to suit the different conditions of use and without altering the pressure of the motive fluid.

Furthermore, it often happens that the drills become lodged in the drill-holes, and very great difficulty is experienced in releasing them.

A further and important object is to provide simple, novel, and effective means whereby the full power of the motor-feeding mechanism, if necessary, can be employed to detach the drill should it thus become fast in the drill-hole.

Still another object is to provide means whereby the drill may be conveniently rotated.

While the invention is susceptible of embodiment in a variety of ways, the preferred form of construction is illustrated in the accompanying drawings, wherein—

Figure 1 is a side elevation of the mechanism. Fig. 2 is a top plan view of the same. Fig. 3 is an elevation of the rear end of the upper portion of the mechanism. Fig. 4 is an elevation of the front end of the same. Fig. 5 is a horizontal sectional view through

the structure, and Fig. 6 is a vertical cross-sectional view.

Similar reference-numerals designate corresponding parts in all the figures of the drawings.

In the embodiment illustrated a support is employed comprising an upright standard 7, having a foot 8 at its lower end and a clamping-screw 9 threaded into its upper end. A right-angularly-disposed arm 10 has a split clamping-collar 11, that is slidably mounted on the standard and is capable of being secured at any desired position thereon, the sections of said collar being held together by tie-bolts 12. Slidable on the horizontal arm 10 is another clamping-collar 13, provided with an upstanding sectional socket-piece 14, forming one member of a swivel. The other end of this swivel comprises a head-plate 15, having a depending stud 16, that is journaled in the socket. The head-plate 15 is provided with an intermediate longitudinally disposed guideway 17, and on opposite sides thereof are upstanding ears 18, carrying split clamping-collars 19. It will of course be understood that the standard 7 may be of any suitable height desired and that it may be rigidly clamped in position by the screw 9. Furthermore, the arm 10, while adjustable on the standard, may be secured at any point by the clamping-collar 11. In like manner the collar 13 is adjustable longitudinally and rotatably upon the arm 10, but can be held at any point thereon, and the head 15 while rotatable with respect to the collar 13, can also be rigidly clamped. Thus said head is capable of a wide range of adjustment with respect to the supporting-standard 7.

Slidably mounted on the head 15 is the motor. While this motor may be of any desired character, it is preferably of the reciprocating piston type and, briefly described, is constructed as follows: An outer casing 20 is provided on its under side with a longitudinally-disposed slide 21, that is movable in the guideway 17. The outer casing has a cross-head 22 at one end and a cap 23 fitted on the other end. Said casing is also provided with an annular internal channel 24, with which communicates a motive-fluid-supply pipe 25. Rotatably mounted in the casing 20 is an inner casing 26, constituting the cylinder

proper of the motor, and operating therein is the usual reciprocatory hammer-piston 27. It is believed to be unnecessary to enter into a description of the operation of this hammer, as the same is well understood. Suffice it to state that the motive fluid from the annular channel 24 of the outer casing finds access to the interior of the inner casing through a plurality of ports 28, communicating with said annular channel. The inner casing 26 at one end has a seat in which is fitted a bearing-collar 29, having a tool-receiving socket 30, that is angular in cross-section. A plug 31 is threaded into the opposite end of the casing and has an angular projecting stud 32. A shaft 33 is journaled in the cap 23 and has a cap 34, that fits over the stud 32. A pinion 35, secured to the outer ends of the shaft 33, is in mesh with a gear-wheel 36, carried by a hand-wheel 37, journaled on a spindle 38, secured to the rear end of the outer casing, as clearly shown in Figs. 1 and 2. The cross-head 22 has a tool-receiving socket 39, which is alined with the socket 30, and a drill or tool stem 40 has an enlarged flange or collar 41, that fits in the socket 39, said tool-stem also having an angular inner portion 42, that engages in the angular socket 30 of the inner casing.

From the above it will be evident that the hammer-piston 27 will be actuated by the motive fluid supplied from the pipe 25 and will operate upon the inner end of the tool-stem. At the same time by turning the hand-wheel 37 the inner casing will be revolved, so that both the hammer-piston and the drill will also be rotated.

Perhaps the most important feature of the invention is the means for feeding the motor and the drill or other tool carried thereby to their work. This means is preferably constructed as follows: Cylinders of different diameters (designated, respectively, 43 and 44) are adjustably mounted in the clamps 19 and are normally held thereby against movement. Operating in these cylinders are pistons 45 and 46, also of different diameters. Piston-rods 47, connected to the pistons, project from the cylinders and pass through the ends of the cross-head 22 of the outer casing 20, being held in position by nuts 48. It will be observed that these nuts have inner reduced portions 49, and journaled upon one of the reduced portions is one end of a latch 50. The other end has a slot 51, that receives the reduced portion of the other nut. An intermediate slot 52 receives the drill-stem. The width of the slot is less than the flange or enlargement 41 of said stem. The cylinders 43 have connected to their end portions feed-pipes 53, which pipes communicate with the cylinders on opposite sides of the pistons. Controlling and relief valves 54 are located in the end portions of the pipes. The pipes are supplied from the pipe 25 through flexible hose-couplings 56. By this arrangement it will be apparent that the motive fluid may be supplied independently to either cylinder or to both simultaneously and on either side of each piston or on both sides simultaneously. This is an exceedingly important feature, as it allows the drill and motor to be fed to their work under varying degrees of pressure. To make this clear, let it be assumed that the rear side 57 of the piston 46 has an area of one inch and the opposite side 58 an area of .40 inch. In like manner assume that the rear side 59 of the piston 45 has an area of .78 inch, and the opposite side 60 an area of .35 inch. The cross-sectional area of the piston-rod 47 will thus be .60 inch, and the cross-sectional area of the piston-rod 47 will be .43 inch. If now the air or motive fluid is at a pressure of one hundred pounds to the square inch, it will be evident that if this motive fluid is admitted to the cylinder 44 at the rear side of the piston 46 or against the surface 57 the feeding pressure upon the motor will be one hundred pounds. If, however, the motive fluid is admitted to the cylinder 44 on both sides of the piston 46, then the effective pressure upon the piston will be sixty pounds. On the other hand, if air is turned into the cylinder 43 against the rear side 59 only of the piston 45 the pressure will be seventy-eight pounds. If turned into the cylinder on both sides of the piston 45, the pressure will be partially counterbalanced and the resultant power secured will be forty-three pounds. Again, if the motive fluid is turned into both cylinders, but against the rear sides 57 and 59 of the pistons only, then the pressure will be equal to the sum of one hundred and seventy-eight pounds. If admitted to both ends of both cylinders, the result will be one hundred and three pounds pressure; but the motive fluid may also be admitted against the surfaces 57 and 59 and against 58 or 60 separately, so that still other variations may be secured. In fact with two cylinders twelve different feeding pressures upon the motor may be obtained, and if still other cylinders and pistons are added it will be clear that the varying pressures may be manifested indefinitely. In connection with this feeding means the latch 50 is an important feature. It is a well-known fact that drills often become securely lodged in the drill-holes, and, as the drill-stems are loosely fitted in the motors, said motors cannot ordinarily be employed for withdrawing the same. By means of the latch engaging the drill-stem and being located outside the enlargement it will be evident that if motive fluid is admitted to the cylinders 43 and 44 against the front sides 58 and 60 only of the pistons the motor will be moved rearwardly, and the latch 50, engaging the enlargement

41 of the stem, will move the stem with the motor, and thus withdraw it from the drill-hole. At the same time the latch will not interfere with the detachment or engagement of the drill with the motor, for it may be freely swung to an inoperative position, as will be evident by reference to Fig. 4.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus fully described my invention, what I claim as new, and desire to secure by Letters Patent, is—

1. In mechanism of the class described, the combination with a motor, of a plurality of fluid-actuated feeding devices for moving the motor, and means for admitting motive fluid to one or more of the feeding devices to vary the pressure thereof upon the motor.

2. In mechanism of the class described, the combination with a motor, of means for feeding the same to its work, said means including a plurality of cylinders and pistons, and means for admitting motive fluid to one or more of the cylinders.

3. In mechanism of the class described, the combination with a motor, of means for feeding the same to its work, said means including a plurality of cylinders and pistons, and means for admitting motive fluid to each cylinder independently of the other and on either or both sides of the piston of such cylinder.

4. In mechanism of the class described, the combination with a motor, of means for feeding the same to its work, said means including a plurality of cylinders and pistons, and means for separately admitting motive fluid to each cylinder on either or both sides of the pistons thereof, or simultaneously to all of the cylinders on either or both sides of the pistons thereof.

5. In mechanism of the class described, the combination with a motor, of a plurality of fluid-actuated feeding devices of different powers for moving the motor, and means for admitting actuating fluid to either of the feeding devices to vary the pressure thereof upon the motor.

6. In mechanism of the class described, the combination with a motor, of a plurality of fluid-actuated feeding devices of different powers connected to the motor for moving the same; and means for admitting actuating fluid to either of the feeding devices separately or to all simultaneously.

7. In mechanism of the class described, the

combination with a motor, of a plurality of fluid-actuated feeding devices, for moving the motor, said devices comprising cylinders and pistons of different areas operating therein, and means for admitting motive fluid to either or both of the cylinders.

8. In mechanism of the class described, the combination with a motor, of a plurality of fluid-actuated feeding devices for moving the motor, said devices comprising cylinders and pistons of different areas operating therein, and means for admitting motive fluid to either or both of the cylinders, and on either or both sides of the pistons thereof.

9. In mechanism of the class described, the combination with a motor, of a plurality of fluid-actuated feeding devices connected to the motor for moving the same, said devices being located at different sides of the motor, and means for admitting motive fluid to each feeding device independently of the other.

10. In mechanism of the class described, the combination with a motor, of a plurality of fluid-actuated feeding devices connected to the motor for moving the same, said devices being located at different sides of the motor and comprising cylinders and pistons operating in said cylinders, and means for separately supplying motive fluid to each of the cylinders to feed the motor by one or more of the devices.

11. In mechanism of the class described, the combination with a motor, of a plurality of fluid-actuated feeding devices connected to the motor for moving the same, said devices being located on opposite sides of the motor and comprising cylinders and pistons of different diameters, and means for supplying motive fluid separately to each of the cylinders.

12. In mechanism of the class described, the combination with a support, of a motor having a cross-head, cylinder members located on opposite sides of the motor, piston members operating in the cylinder members, certain of said members being connected to the cross-head, the others being connected to the support, and means for introducing motive fluid separately into each of the cylinder members.

13. In mechanism of the class described, the combination with a support, of a motor having a cross-head, cylinders of different diameters located on opposite sides of the motor and connected to the support, piston members of different diameters operating in the cylinders and connected to the cross-head, and means for introducing motive fluid into any or all of the cylinders upon either or both sides of the pistons therein.

14. In mechanism of the class described, the combination with a support including clamps and a guideway mounted between the

- clamps, of a motor slidably mounted on the guideway, cylinders secured to the support by the clamps, pistons operating in the cylinders and connected to the motor, and 5 means for admitting motive fluid to the cylinders.
15. In mechanism of the class described, the combination with a support, of a motor thereon, cylinders adjustably secured to the support, pistons operating in the cylinders and connected to the motor, a motive-fluid-supply pipe connected to the motor, separate pipes connected to the cylinders on opposite sides of the pistons, controlling-valves there-in, and flexible conduits connecting the supply-pipe and the pipes of the cylinders.
16. In mechanism of the class described, the combination with a support including a head, said head having a longitudinally-disposed guideway, and clamps disposed on opposite sides of the guideway, of a motor including a cylinder slidably mounted in the guideway, feeding devices comprising cylinders of different diameters, adjustably held by the clamps and located on opposite sides of the motor, pistons of different diameters operating in the cylinders and connected to the motor, and means for admitting motive fluid to the motor and to the cylinders on opposite sides of the pistons.
17. In mechanism of the class described, the combination with a support, of a motor movably mounted thereon, a feeding device comprising a cylinder member and a piston member operating therein, a clamp engaging one member and connected to the support for holding said member against movement thereon, and means connecting the other member to the motor.
18. In mechanism of the class described, the combination with a support, of a motor movably mounted thereon, a feeding device comprising a cylinder member and a piston member operating therein, a clamp mounted on the support and embracing the cylinder member to hold it against movement thereon, and means connecting the piston to the motor.
19. In mechanism of the class described, the combination with a support, including a head, and a guideway formed in the head, of a motor having a slide movable in the guideway, a clamp carried by the head, a cylinder engaged and secured by the clamp, and a piston operating in the cylinder and connected to the motor.
20. In mechanism of the class described, the combination with a motor, of means for feeding the same to and withdrawing it from its work, a tool-stem operated on by the motor, and a latch pivoted at one end to the motor and having its axis of movement substantially parallel to the same, the other end of the latch having a detachable engagement with the motor, and an intermediate portion 65 of such latch detachably engaging the tool-stem.
21. In mechanism of the class described, the combination with a motor, of means for feeding the same to and withdrawing it from its work, said means including a cylinder and a piston operating in the cylinder and connected to the motor, a tool operated on by the motor, and a latch pivoted on the piston connection and having a detachable engagement with the tool.
22. In mechanism of the class described, the combination with a motor having a tool-receiving socket, of fluid-actuating means for moving the motor including a cylinder 70 member and a piston member, a connection between one of said members and the motor, a tool having a stem that engages in the socket, and a latch mounted on the said connection and engaging the tool-stem to move 75 it with the motor during the movement of said motor in one direction.
23. In mechanism of the class described, the combination with a motor having a head at one end, and a tool-receiving socket that 80 extends through the head, of fluid-actuate means for moving the motor, said means comprising cylinders located on opposite sides of the motor, pistons operating in the cylinders, and piston-rods carried by the pistons 85 and connected to the head of the motor, a tool-stem having an enlargement that engages in the tool-receiving socket, and a latch pivotally mounted on one of the piston-rods and detachably engaging the other, said 90 latch having an intermediate portion that extends across the tool-receiving socket and the enlargement of the stem that is located therein.
24. In mechanism of the class described, the combination with an outer casing, of an inner casing revolvably mounted in the outer casing, a piston-hammer operating in the inner casing, said inner casing having an angular socket in one end, and an angular stud 95 projecting from its other end, a tool having an angular portion slidably mounted in the socket and rotatable with the casing, a shaft 100 projecting through the outer casing and having a cap that fits over the stud, and means 105 for rotating the shaft.
25. In mechanism of the class described, the combination with an outer casing having an angular fluid-conducting channel, of motive-fluid-supply means communicating with 110 the channel, an inner casing rotatably mounted in the outer casing and having ports communicating with the channel of the outer casing, said inner casing having an angular socket in one end, and a stud projecting from 115 its other end, a tool having an angular stem projecting through the socket, a reciprocatory hammer-piston operating in the inner 120
- 125

casing against the tool-stem, a shaft journaled in the outer casing and having a cap that engages the shaft of the inner casing, the end of the shaft having a pinion and a hand-wheel rotatably mounted on the outer casing and having a gear-wheel meshing with the pinion.
